DEFECTIVELY LABELED AND NONLABELED
CAN DETECTING DEVICE

George J. Palmer, Long Beach, Calif.

Application October 25, 1948, Serial No. 56,314

12 Claims. (Cl. 209—72)

1

My invention relates to a defectively labeled and non-labeled can detecting device, and is a continuation in part of my pending application Serial No. 768,114, now Patent No. 2,560,737.

A major object of my invention is to provide a completely integrated defectively labeled and non-labeled can detecting unit which can be removably supported from the can bearing guide means of the device shown in my pending application. Although the detecting means disclosed in my prior application has proved to be satisfactory in operation, I have found my present invention to be more sensitive to defectively labeled cans, as well as being more convenient to install and use. In addition, due to the increased sensitivity of my present detecting device it is adapted to be used with labelers having a higher discharge rate of cans than is possible with the detectors disclosed in my prior application.

Another object of my invention is to provide a can detecting unit having an extremely simple mechanical structure, that can be easily fabricated from standard commercially available material, is relatively inexpensive to produce, and simplifies the making of repairs on the device disclosed in my prior application in that a new detecting unit can be installed therein with the expenditure of but a minimum of time and effort.

These and other objects and advantages of my invention will become apparent from the following description of a preferred form thereof, and from the drawings illustrating that form in which:

Fig. 1 is an end elevational view of my defectively labeled and non-labeled can detecting device;

Fig. 2 is a vertical cross-sectional view of the device taken on the line 2—2 of Fig. 1;

Fig. 3 is an enlarged vertical cross-sectional view of a vacuum breaking valve used in connection with the device;

Fig. 4 is a vertical cross-sectional view of one of the sets of resilient electrical contact elements and supporting housing used in the device, with a diagrammatic wiring diagram being shown in connection therewith; and,

Fig. 5 is a plan view of one of the sets of resilient electrical contact elements and its insulated supporting housing.

Referring now to Figs. 1 and 2 for the general arrangement of my defectively labeled and non-labeled can detecting device it will be seen that the device includes an inverted U-shaped member 10 and an L-shaped sheet metal member 11

2

which are removably held together by screws 12 to provide a substantially rectangular frame. The frame is formed into a completely enclosed container 13 by side walls 14 and 15, each of which is affixed by screws 16 to the member 10. The container 13 is provided with two electrically insulated housings H, with each of the housings extending longitudinally along the upper portion of one of the side walls thereof. The housings H with the container 13 situated therebetween are disposed between the laterally spaced can bearing rails 98. In referring to component parts of my present invention which are not only common to it but to the device shown in my pending application as well, the numerals used in the pending application will also be used in the present application for the sake of clarity.

In Fig. 1 it will be seen that a number of screws 19 engage bores formed in the rails 98 and the 20 housings H to removably hold the container 13 in the desired position between the rails.

The member 10 is formed with a substantially short vertical leg 20, a connecting web 21 that is positioned flush with the upper horizontal surface of the rails 98 over which the cans C roll, and a leg 22 that is parallel to and considerably longer and thicker than the leg 20. Although the member 10 may be fabricated from any substantially rigid material, I have found it convenient to cast these members from one of the relatively light metals such as aluminum or magnesium. In Fig. 2 it will be noted that the leg 22 has a substantially vertical bore 23 formed therein, which is in communication with an intermediately positioned horizontal bore 24. The bore 24 on one end develops into a bore 25 of somewhat larger diameter with which it forms an annular vertical body shoulder 26, and on the opposite end develops into a horizontal bore 27 of substantially smaller diameter. The bore 25 is adapted to receive an annular diaphragm 28 having an intermediately positioned annular corrugation 29 formed therein, with the diaphragm being seated against the body shoulder 26, and held in place thereon by an annular ring 30.

A tubular member 31 formed of an electrical insulating material is positioned in the bore 27, with the outer end of the member contacting a rectangular sheet of insulating material 32 which is positioned on the exterior face of the leg 22. A metallic plate 33 having the same overall dimensions as the plate 32 is situated on the outer face thereof.

A horizontal bore 34 is formed in the upper 55 portion of the plate 33, and is in alignment with

bore formed in the plate 32 and leg 22, with the bore in leg 22 having a tubular electrical insulator 35 inserted therein. A screw 36 passes through the bore 34, the bore formed in plate 32, and through the insulator 35, with the inwardly disposed end of the screw being provided with an electrical insulating washer 37 and nut 37a for reasons which will hereinafter be explained. A screw 38 serves to hold the plate 33 in place by extending through a tubular electrical insulator 38a which is positioned in a bore formed in the plate to engage a tapped bore formed in the leg 22. The insulator 38a on its outer end is provided with a lip or insulating washer to prevent the screw 38 from serving as an electrical conductor between the plate 33 and the leg 22.

A threaded metallic rod 40 engages a centrally disposed tapped bore 39 formed in the plate 33, with the rod extending through the insulator 27 and being provided on its outer end with a handle 41. By rotating the handle 41 the inner end 42 of the rod may be brought into the desired relationship with the diaphragm 28 for reasons which will hereinafter be explained.

A conventional pipe fitting 43 which is adapted to receive the threaded end portion of a tube 44 is affixed to the lower surface of the member 11 and is in communication with the bore 23. The tube 44 extends to a T-shaped pipe fitting 45 that is affixed to the suction side of a vacuum pump 46. The upper end of the fitting 45 engages a conventional fitting 46a which is adapted to receive a vacuum breaking valve 47 the details of which can best be seen in Fig. 3.

The valve 47 includes an externally threaded cylindrical plug 48 having a number of vertically positioned bores 49 extending downwardly therethrough. Plug 48 is formed with a centrally disposed vertical bore 50 in which a screw 51 is slidably mounted in an inverted position. A rigid washer 52 and a washer 52a formed from a resilient material are mounted between a screw head 53 and the lower face of the plug 48. A helical spring 54 encircles the upper portion of the screw 51 with the lower end of the spring contacting the upper face of the plug 48, and the upper end of the spring in contact with the lower face of one of two nuts 55 which are threaded on the screw.

To use my device in detecting loosely labeled cans, an insulated conductor 145 is connected to the diaphragm holding ring 30 in a conventional manner, and a conductor 153 to the screw 36. The vacuum pump 46 is now started, with the result that a current of air is drawn downwardly through the bore 23 and tube 44. The handle 41 is rotated to bring the rod portion 42 relatively close to the diaphragm 28 in order that as the diaphragm is deformed inwardly by a vacuum being formed in the bore 23 an electric circuit is completed between the conductors 145 and 153 to energize the electronic circuit used in actuating the can ejecting mechanism disclosed in my prior application.

Upon a loosely labeled can rolling along the rails 98, the loose label for an instant is drawn downwardly by the stream of air passing into the tube 23, with the result that the entrance to the bore 23 is momentarily obstructed, and during this period a vacuum is formed in the bore which deforms the diaphragm inwardly to make contact with the rod portion 42. The volume of air being drawn downwardly through the bore 23 to quickly achieve a vacuum would normally result in such instantaneous deforming of the

diaphragm 28 that it would be punctured or ruptured on the rod portion 42. Although the vacuum is quickly formed it is not carried beyond a predetermined degree due to the action of the vacuum breaking valve 47. As a vacuum is applied to the valve 47 the washers 52 and 52a are pulled downwardly to admit the air to the pump 46 through the bores 49 which air would normally be supplied to the pump through the bore 23.

Upon the loosely labeled can having passed beyond the bore 23 air is again permitted to be drawn downwardly through the bore 23 and tube 44 into the pump 46, with the result that the compression on the helical spring 54 causes the screw 51 and washers 52 and 52a to move upwardly to obstruct the bores 49 until such time as the entrance to the bore 23 is momentarily closed by the loose label on one of the cans C coming in contact therewith.

Situated within the confines of the container 13 is a snap switch 116 having a vertically movable pin 57 that extends upwardly through an opening formed in the web 21, with the pin on being depressed momentarily by a rolling can C breaking the power supply to the tube 101 and permitting the grid 123 to obtain control of the electronic circuit as described in my pending application. Thus, each time one of the cans C depresses the pin 57 the can ejecting mechanism is placed in a non-actuating condition, and is not actuated until the presence of a non-labeled or loosely labeled can is signaled by one of the detecting devices.

In a detecting and ejecting device in which the defectively labeled and non-labeled cans are displaced from the rails 98 by impact from a solenoid operated member 163 as shown in Figs. 16 and 17 of my pending application, trouble is occasionally encountered by a loose label falling in front of the rolling can to momentarily obstruct the entrance to the bore 23 before the can C having the loose label is in a position to be ejected by the member 163. To eliminate this condition, the electrical contact means shown in Figs. 4 and 5 are employed. It will be noted that each of the housings H has an inverted L-shaped recess 60 formed along each side thereof, with the outer recess being provided at its forward end with a screw 61. Supported in the outer recess 60 by the screw 61 is an inverted L-shaped member 62 that is formed from a resilient electrical conducting material, with the member having an upturned leg 63 which is positioned in the vertical portion of the recess to project above the upper surface of the housing H.

Situated near the vertical leg portion of the recess 60 is a machine screw 64 that serves as an electrical contact member which is engaged by the lower portion of the member 62 as one of the cans C rolls over the member 63. In Figs. 4 and 5 it will be noted that the conductor 153 is connected to the screw 61, and the conductor 145 is connected to both the diaphragm holding ring 30 and the can supporting rails 98. An insulated electrical conductor 65 extends from the electrical contact 64 to the screw 36. Thus, upon a perfectly labeled or non-labeled can rolling over the electrical contact member 63, the member 62 is moved downwardly and brought in contact with the screw 64. However, an electrical circuit is not established from such movement of the member 62 as the circuit between the conductors 145 and 153 is incomplete due to the diaphragm

28 and rod portion 42 being out of contact with one another.

Upon a loosely labeled can rolling along the rails 98, and the label momentarily covering the entrance to the bore 23, the diaphragm 28 is deformed inwardly as previously described to make contact with the rod portion 42. Such an action, however, does not actuate the solenoid operated ejecting member 163 until the can C is actually in a position to be ejected by the member which is signaled by the can rolling over the member 63. Upon the member 63 being depressed, the member portion 62 is brought in contact with the electrical contact 64 which completes the circuit between the conductors 145 and 153 to energize the electronic circuit described in my pending application. Thus, in effect I have a delayed action detecting device for a loosely labeled can, with the label obstructing the bore 23 to place the circuit in a condition to be completed which is only accomplished when the can C contacts the member 63. It will be apparent that in this type of detecting device the bore 23 and the contact member 63 must be in substantially the same vertical plane. In the event the member 63 is disposed rearwardly from the bore 23, the portion of the circuit formed by a loosely labeled can obstructing the bore would be broken by the can moving beyond the bore 23 before contacting the member 63.

In Fig. 5 it will be noted that the inwardly disposed recess 60 has an electrical contact member 62a situated therein that is identical to the previously described member 62. However, the member 62a is electrically connected to the conductor 145 as is the can supporting rail 98. Upon a non-labeled can rolling along the rails 98 and contacting the members 63 and 63a an electrical circuit is immediately established between the conductors 145 and 153 to energize the electronic circuit used in controlling the can ejecting member 163. From the electrical diagram shown in Figs. 4 and 5 it will be apparent that a non-labeled metallic can will cause an electric circuit to be completed between the conductors 145 and 153 either by contacting the members 63 and 63a, or the member 63 and the rail 98.

By laterally adjusting the member 62 with relation to the rail 98, either by means of shims or other conventional means such as a screw, the sensitivity of my detecting device to cans having mis-aligned labels thereon can be controlled. Should a can having a mis-aligned label thereon travel over the rails 98, the bare portion of the can will engage the member 63 and the rail 98 to complete an electric circuit between the conductors 145 and 153 to energize the electronic circuit which controls the can ejecting member 163. Thus, the closer the member 62 is situated to the adjoining rail 98, the greater will be the sensitivity of my device in ejecting cans that have labels that are mis-aligned. Although I have described but one of the housings H used on my detecting device, the housing H disposed on the opposite side thereof is identical in construction and operates in the same manner. To prevent the member 62 or 62a coming in contact with the rails 98 or the side walls of the container 13, a sheet of electrical insulating material 70 is provided for and disposed between the longitudinal sides of the housing and the contacting portions of the container 13 and rail 98.

The particular wiring arrangement which I have found convenient to use in my detecting unit is best seen in Fig. 2. In the first described

form of my device a two-way plug 80 is provided in which the ends of the electrical conductors 145 and 153 leading to the electronic circuit controlling the can ejecting mechanism may be removably inserted. A continuation of the conductor 153 extends from the plug 80 to the member 61 and the inwardly disposed end of the screw 36. In a similar manner a continuation of conductor 145 proceeds from the plug 80 to the annular ring 30 to which it is affixed in a conventional manner. Leading from the snap switch 116 are the electrical conductors 114 and 117 which terminate in a three-way plug 81 that can be situated in a convenient location on the device shown in my pending application. The conductor 114 continues to the electronic circuit from the plug 81, while the plug serves as the junction point 130 for the conductor 117 which is joined therein to the conductor 128. The electrical conductor 127 is joined to the conductor leading to the cathode 124 at the plug 81.

Should it be desired to use the delayed action type of detecting device previously described, the conductor 153 between plug 80 and screw 36 is eliminated, and conductor 65 shown in phantom line is extended from the screw 36 to electrical contact 64. The detecting unit then completes the electric circuit between conductors 145 and 153 only when the can C to be ejected rolls over the contact member 63.

Although the defectively labeled and non-labeled can detecting device herein shown and described is fully capable of achieving the objects and providing the advantages hereinbefore stated, it is to be understood that it is merely illustrative of the presently preferred embodiment of my invention, and that I do not mean to limit myself to the details of construction herein shown and described other than as defined in the appended claims.

I claim:

1. A switch for detecting loosely labeled and non-labeled cans which includes: a housing formed from an electrical insulating material, 45 with said housing having a recess on each side thereof, and said housing being adapted to be situated adjacent to one of two laterally spaced metallic rails over which cans roll; a resilient metallic member situated in said recess adjacent to said rail; means for spacing said member relative to said rail whereby the sensitivity of said switch is regulated; means for affixing an electrical conducting member to said resilient member; an electric contact mounted on said housing and adapted to be engaged by said member as a can rolls over a projecting portion of said member, with said electric contact being adapted to have an electrical conductor affixed thereto which extends to a vacuum actuated switch that is closed by a loosely labeled can rolling over a predetermined area; a second resilient metallic member mounted in the other of said recesses; metallic means for holding said member in said recess, with said means being adapted to have an electrical conductor affixed thereto which conductor is also connected to said rail whereby a non-labeled can completes an electric circuit to actuate a can ejecting device by simultaneously engaging either said first and second members or said first member and said rail, and a loosely labeled can actuating said can ejecting device by moving said first member to complete a circuit between said first member holding means and said electric contact through said vacuum actuated switch.

2. A device to detect and eject loosely labeled cans which includes: a pair of rails over which a plurality of cans roll; a housing positioned below and between said rails, with said housing having a passage extending downwardly from the upper face thereof; means to draw a stream of air through said passage; a resilient member mounted in said housing and in communication with said passage, with said member being deformed by a vacuum formed in said passage as a loose label on one of said cans momentarily blocks the entrance to said passage; a normally open electric circuit; a can ejecting device that is actuated by the completion of said circuit; electrical means to close a portion of said circuit upon said member being deformed; a member that is moved by each of said cans; and electrical contact means associated with said member that completes said circuit when said member is moved and said resilient member is deformed.

3. A device to detect and eject loosely labeled cans which includes a pair of rails over which a plurality of cans roll; a housing positioned below and between said rails, with said housing having a passage formed therein, and one of the entrances to said passage formed in the faces of said housing between said rails; means to draw a stream of air through said passage; a resilient diaphragm mounted in said housing and in communication with said passage, with said diaphragm being deformed by a vacuum formed in said passage as a loose label on one of said cans is drawn into a position by said stream of air to momentarily block the entrance to said passage; a normally open electric circuit; a can ejecting device operatively associated with said rails that is actuated by the completion of said circuit; electrical contact means to partially close said circuit upon said diaphragm being deformed; and electrical contact means that complete the closing of said circuit upon said can having the loose label that blocks the entrance to said passage reaching a predetermined position relative to said housing.

4. A device to detect and eject loosely labeled cans which includes: a pair of rails over which a plurality of cans roll; a housing positioned below and between said rails, with said housing having a passage formed therein, and one of the entrances to said passage being formed in the face of said housing positioned between said rails; means to draw a stream of air through said passage; a resilient diaphragm mounted in said housing and in communication with said passage, with said diaphragm being deformed by a vacuum formed in said passage as a loose label on one of said cans is drawn into a position by said stream of air to momentarily block the entrance to said passage; a normally open electric circuit; a can ejecting device operatively associated with said rails that is actuated by the completion of said circuit; electrical contact means that partially close said circuit upon said diaphragm being deformed; a member that is moved as each of said cans pass over said rails; and electrical contact means that are engaged as said member is moved to complete said circuit only when said diaphragm is deformed.

5. A device to detect and eject loosely labeled cans which includes: a supporting means over which a plurality of cans roll; a housing below said supporting means and in the path of said cans, with said housing having a passage extend-

ing downwardly from the upper face thereof; means to draw a stream of air through said passage; a resilient diaphragm mounted in said housing and in communication with said passage, with said diaphragm being deformed by a vacuum formed in said passage as a loose label on one of said cans is drawn into a position by said stream of air to momentarily block the entrance to said passage; a normally open electric circuit; a can ejecting device operatively associated with said rails that is actuated by the completion of said circuit; an electrical contact that is engaged as said diaphragm is deformed; a movable electrical conducting member mounted on said supporting means that is moved as each of said cans pass thereover; an electrical contact that is engaged as said conducting member is moved; and an electrical conducting member connecting said two electrical contacts and completing said circuit only when said diaphragm is deformed and said conducting member is moved.

6. A device to detect loosely labeled cans which includes: pair of rails over which a plurality of cans roll; a housing positioned below and between said rails, with said housing having a passage formed therein through which a stream of air may be continuously drawn, and the entrance to said passage being formed in the face of said housing situated between said rails; a normally open electric circuit; a can ejecting device operating associated with said rails that is actuated upon completion of said circuit; electrical contact means that are actuated to partially complete said circuit upon a vacuum being formed in said passage by a loose label on one of said cans being drawn by said air stream into a passage blocking position; a member mounted on one of said rails that is moved as each of said cans pass thereover; and an electrical contact that is engaged as said member is moved to complete said circuit.

7. A device to detect and eject loosely labeled cans which includes: pair of rails over which a plurality of cans roll; a housing positioned below and between said rails, with said housing having a passage formed therein, and one of the entrances to said passage being formed in said face that is situated between said rails; means to draw a stream of air through said passage; a resilient member mounted in said housing and in communication with said passage, with said member being deformed by a vacuum formed in said passage as a loose label on one of said cans momentarily blocks the entrance to said passage; a normally open electric circuit; a can ejecting device operatively associated with said rails that is actuated by the completion of said circuit; electrical means that close a portion of said circuit upon said member being deformed; electric switch means that close the balance of said circuit upon one of said cans having a loose label coming in contact therewith; and valve means that regulate the extent to which said vacuum can be formed in said passage whereby said resilient member will not be damaged.

8. A device to detect and eject loosely labeled cans which includes: pair of rails over which a plurality of cans roll; a housing positioned below and between said rails, with said housing having a passage formed therein, and one of the entrances to said passage being formed in the face of said housing positioned between said rails; means to draw a stream of air through said passage; a resilient diaphragm mounted in said

housing and in communication with said passage, with said diaphragm being deformed by a vacuum formed in said passage as a loose label on one of said cans is drawn into a position by said stream of air to momentarily block the entrance to said passage; a normally open electric circuit; a can ejecting device operatively associated with said rails that is actuated by the completion of said circuit; electrical contact means to partially close said circuit upon said diaphragm being deformed; electrical contact means to complete the closing of said circuit upon said loose labeled can reaching a predetermined position relative to said housing; and valve means to regulate the extent to which said vacuum can be formed in said passage whereby said diaphragm will not be damaged.

9. A loosely labeled and non-labeled can detecting device and ejecting that includes: a pair of rails over which a plurality of cans roll a housing having a passage formed therein through which a stream of air may be drawn, with said housing positioned below and between said two rails; a resilient diaphragm in said housing that is in communication with said passage, with said diaphragm being deformed upon a vacuum being formed in said passage as a loose label on one of said cans is drawn into a passage obstructing position by said air stream; a normally open electric circuit; a can ejecting device operatively associated with said rails that is actuated by the completion of said circuit; a plurality of laterally spaced movable electrical conductors operatively associated with said rails, and said conductor completing said circuit when contacted by a non-labeled metallic can; an electrical contact that is engaged by one of said conductors as it is moved by a can; an electrical contact that is engaged by said diaphragm as it is deformed; and an electrical conductor connecting said two contacts and completing said circuit when a loose labeled can causes the deformation of said diaphragm and movement of said movable conductors.

10. A loosely labeled and non-labeled can detecting and device which includes: a pair of rails over which a plurality of cans roll a housing having a passage formed therein through which a stream of air may be drawn, with said housing positioned between said rails; a plurality of laterally spaced movable electrical conducting members operatively associated with said rails; a normally open electric circuit; a can ejecting device operatively associated with said rails that is actuated by the completion of said circuit; means that complete said circuit upon a non-labeled metallic can contacting said movable members; and electrical contact means that complete said circuit by a loose label on one of said cans being drawn into a passage obstructing position by said air stream and said loose labeled can moving one of said movable members.

11. A loosely labeled and non-labeled can de-

tecting and ejecting device which includes: a pair of rails over which a plurality of cans roll; a housing having a passage formed therein through which a stream of air may be drawn, with said housing positioned below and between said rails; a resilient diaphragm mounted in said housing and in communication with said passage with said diaphragm being deformed when subjected to a vacuum; a normally open electric circuit; a can ejecting device that is actuated by the completion of said circuit; a movable electrical conducting member operatively associated with said rails that completes said circuit upon being contacted by a non-labeled metallic can; and electrical contact means that complete said circuit upon said diaphragm being deformed by a loose label on one of said cans being drawn into a passage blocking position by said air stream and said movable member being moved by said can causing said diaphragm deformation.

12. A loosely labeled and non-labeled can detecting and ejecting device which includes: a pair of rails over which a plurality of cans roll; a housing having a passage extending downwardly therein through which a stream of air may be drawn, with said housing positioned below and between said rails; a resilient diaphragm mounted in said housing and in communication with said passage with said diaphragm being deformed when subjected to a vacuum; a normally open electric circuit; a can ejecting device operatively associated with said rails that is actuated by the completion of said circuit; a movable electrical conducting member operatively associated with said rails that completes said circuit upon being contacted by a non-labeled metallic can; electrical contact means that complete said circuit only upon a loose label on one of said cans being drawn into a position by said air stream to block said passage and form a vacuum in said passage and said loose labeled can moving said movable member; and valve means regulating the extent to which said vacuum can be formed in said passage to prevent damage to said diaphragm.
